LOW-QUAD MATRIX.

Application filed October 31, 1921. Serial No. 511,673.

To all whom it may concern:

Be it known that we, ADAM G. TEASON, ALEXANDER L. RILEY, and OLIVER C. FORTUNE, citizens of the United States, residing at the city of Kansas City, in the county of Jackson and State of Missouri, have invented certain new and useful Improvements in Low-Quad Matrices, of which the following is a specification.

10 This invention is intended for a labor and time-saver in the use of linotype machines for casting in one piece slugs or lines of type-faces, from which is indirectly produced the common readable line in the daily 15 newspapers or other periodicals or the like. This invention consists of a special matrix devised to be used in connection with such machine, which machine is otherwise known as a type-casting machine. That part of 20 one of the said slugs or lines of type that bears no type-faces is like the quads used in monotype typesetting, either by hand or by machine, and like the said quads frequently projects too high, with the result 25 of making an imprint where none is wanted and thereby spoiling the appearance of the work.

The present practice is to lower the unused or quad-like part of the line of type or 30 slug by using a saw or routing it out. This is, however, a slow and cumbersome method, and the purpose of this invention is to provide mechanical means and a method for casting such slugs with the said unused or 35 blank part adequately lowered. Being thus cast simultaneously with the formation of the line of type or slug, the said routing or sawing is rendered unnecessary. This is obviously a very great advantage and im- 40 provement and time and labor saver in the use of linotype machines.

In the accompanying drawings forming part of this specification, in which like numbers of reference denote like parts wherever 45 they occur,

Figure 1 is a perspective view of a male matrix;

Figure 2 is a perspective view of an elong-

gated male matrix, which like Figure 1 exhibits and embodies this invention;

Figure 3 illustrates a quad matrix such as heretofore in use;

Figure 4 illustrates a female or type matrix such as now in use;

Figure 5 illustrates this invention in the set position;

Figure 6 is a similar view of the quad matrix of Figure 3;

Figure 7 is a similar view of the female or type matrix of Figure 4;

Figure 8 shows this invention in connection with the mold;

Figure 9 illustrates the quad matrix of Figure 3 in connection with the mold;

Figure 10 shows the female or type matrix of Figure 4 in connection with the mold;

Figure 11 illustrates a slug or line of typefaces where the line is incomplete and as cast by present practice and prior to the use of the saw or routing out;

Figure 12 illustrates the said slug after it has been lowered by sawing or routing out and at the same time illustrates the slug as cast by the use of the invention of this method and embodying the construction that is the subject-matter of this invention; and

Figure 13 is a view showing the combination of the matrix with the matrix guide and the mold.

In the figures in the above-mentioned drawings that illustrate this present invention are Figures 1, 2, 5, 8, and 12. The other figures in the drawings are included so as to contrast the present practice with this new invention, and thereby to point out what is new in this present invention.

All the matrices shown in the drawings in figures other than Figures 2, 11, and 12 represent individual characters, either letters or the like or spaces. Thus the matrix shown in Figures 3, 6, and 9 is the old single-space matrix. The matrix shown in Figures 1, 5, and 8 is the new single-space matrix of this present invention.

The difference between the device shown in Figure 1 and that shown in Figure 2 is merely that the latter is longer, the object being to use an elongated male matrix like that shown in Figure 2 instead of a plurality of male matrices like that shown in Figure 1, whenever the line to be filled out is long enough to require filling out more than the equivalent of a space or two. In other words, the male matrix of this invention will be made and used in different lengths, so that if the skilled compositor perceives that a space will be left at the end of the last line in a paragraph equal, for example, to three times the thickness of the matrix of Figure 1, he sets a matrix like that of Figure 2, having dimensions in length of three times the thickness of the matrix shown in Figure 1. He will be provided with an assortment of matrices like that in Figure 2 of various lengths, adapted to suit any space that may be left.

Furthermore, the matrices like those shown in Figures 1 and 2 will be adapted for the various sizes of type, by which is meant that the projection 1 will be larger or smaller as the case may be, just like as in the type 2 the same are larger or smaller. It is to be understood, of course, that the variation in size of type 2 and of the projections 1 does not affect the size of the matrices, as all matrices are of standard size. The only variation in the size of any of the matrices is in the length of the matrix shown in Figure 2, which length arises from the multiplication of the thickness of the matrix of Figure 1.

This invention is intended for use with machines now on the market, substantially the only change necessary being the provision of groove 3 in the back-rail 4, and, of course, the provision of a suitable number of matrices with the projection 1. The matrix of Figure 1 is like the matrix of Figure 3 with the addition of the projection 1.

The provision of groove 3 allows a matrix like that of Figure 1 or of Figure 2 to travel all the way from the assembler to the mold without other change in the machine. As soon as the matrix of this invention has performed its function, it is automatically released into a pan of the first elevator, there ready to be used again. The assembler, conveyor, releasing mechanism, elevator, and magazine are not shown in the drawings, because they do not constitute parts of this present invention but are parts of the well-known machine.

The lowering of the untyped part 5 of the slug 6 is done by hand, and constitutes a second handling thereof in current practice, but this second handling for the purpose of lowering the said part to look like the face 7 in Figure 12 is by the present

invention eliminated, as with the use of the present invention the slug 6 is cast with the lowered face 7, as it appears in Figure 12. This is caused by the way the metal flows into the mold 8, as shown in Figure 8, the projection 1 in Figure 8 evidently producing an effect in holding the molten metal the opposite of the effect produced by the female part or type 2 in Figure 10 and, also, a greater elevation (which results in depression of face 7 in Figure 12) than the plain face on the side of the matrix in Figure 9. Otherwise stated, the lowered face 7 on the slug 6 in Figure 12 is caused by the projection of the part 1 of the male matrix of Figures 1 and 2 into the mold 8 in Figure 8.

The projection 1, as well as matrices to which it is attached, can be made of any material that will withstand the heat of the molten metal.

The groove 3 must be large enough (i. e. wide enough) to accept the largest size of projection 1 used to pass through, the size of the said projection 1 depending upon the size of the type used in casting the accompanying line of type-faces.

Skilled operators are likely to find uses for the device of this invention other than that described herein, such, for instance, as using the same between words or figures as spacers, inasmuch as they will ride any place where they are put in conjunction with the female matrices or will cast an entire slug 6, if enough be put in the assembler to fill the said space.

The projection 1 can be made of any thickness or height, provided that its thickness be not too great to be taken care of by the mold provided. Of course, as mentioned, the mold can be changed when needed in special cases. By the mold is meant the mold on the typecasting machine (not shown in the drawings).

We term the devices of this invention low quad matrices. Some slight change in the machine and magazine so as to allow the same to be fed automatically from the magazine may be necessary, but none is necessary when the same are inserted by hand, although both time and labor can be saved when the same are used by putting them into the assembler by hand.

The old process of sawing or routing the slugs is accomplished by a circular saw or routing machine and with great labor and requires vast dexterity on the part of the workman, so as not to saw too far or to get the lines transposed from their original position while being handled in this slow and cumbersome manner, as in most cases each slug or line of type must be handled separately and individually at the saw or routing machine. Frequently much valuable time is wasted in the composing room where

these slugs are assembled into their respective forms, and where all slugs or lines of type have not been routed or sawed as required at the place of casting, where usually a saw for that purpose is at hand. When thus defective the cutting must be completed by hand by the compositor who is making up the form or the slug must be sent back to the place of casting. If done by hand by the compositor it is performed upon a hand slug-cutter designed for that purpose. When this hand cutter is used the blank part of the slug that is the face 5 in Figure 11—that part of the slug upon which no type-faces appear, must be completely cut off, which then entails the trouble of the workman piecing together foundry leads and slugs which are manufactured low enough so as to be out of the way of the inking rollers of the printing press, because the hand slug-cutter will not perform the same work that the saw or routing machine will, and the foundry leads and slugs must be put in the place of that part 25 of the slug which has been cut off to facilitate a perfect lock-up, which is requisite before being allowed to go to the press. It can readily be seen that a great loss of time is thus caused where several forms per day 30 are handled. Moreover, it frequently happens that the high face 5 will pass unnoticed by the most watchful compositor and then cause more trouble for the pressman, whose duty it is to print a clean, clear piece of 35 work regardless of difficulties. This necessitates his bringing the form back to the stoneman for correction, that is to have the high parts cut away, but sometimes the pressman will take a common chisel and 40 spend a lot of time hacking at the high parts until, in his judgment, they have been made low enough by this hacking not to show in the printed sheet. If not low enough an ill-looking job of printing is turned out. 45 Thus it can be seen that a detail so seemingly unimportant as the method now in common use failing to produce a slug with the unused part sufficiently lowered not to be inked by the inking rollers of the press 50 passing over them, is really quite important and expensive.

This invention consists in substituting for the old quad matrix made to set smoothly against the face of the mold to keep back the flow of the molten metal, so as not to be type high, a quad matrix having the projection 1, extending from the mold edge at the point where the depression appears in the female matrix which projection 1 is 55 adapted to extend into the slot of the mold of the typecasting machine to any required depth to keep back the flow of the molten metal from the type-high part of the slug to a depth greater than according to present 60 practice with the old quad matrix of Figure 65

3. By thus keeping back the flow of the molten metal to such greater depth, the lowered face 7 on slug 6 in Figure 12 is produced. This invention, furthermore, consists in the method by which the said result 70 is obtained.

Having thus described this invention, we hereby reserve the benefit of all changes in form, arrangement, order, or use of parts, as it is evident that many minor changes 75 may be made therein without departing from the spirit of this invention or the scope of the following claims.

We claim:

1. The combination with a mold cavity 80 and a guide groove in horizontal alinement therewith; of a quad matrix consisting of a metallic plate of uniform thickness throughout and having a type mold confronting edge provided intermediate its ends with a lateral projection formed integrally with the matrix and immovable with respect thereto, said projection being adapted to completely fill the width of the mold space of a type mold when the matrix 85 is applied thereto, the guide groove in the mold plate being of greater cross sectional dimensions than the intermediate projection whereby said intermediate projection fits 90 freely therein. 95

2. The combination with a mold cavity and a guide groove in horizontal alinement therewith; of a quad matrix consisting in a single plate of metal having all parts integral therewith and thereby immovable with respect to each other, said plate having one edge constituting a mold confronting edge and provided at its top and bottom corners with lateral projections, said plate having a projection on the mold confronting edge intermediate the aforesaid lateral projections and extending from the body of the matrix a distance substantially equal to said first projections, the width of the intermediate projection being sufficient to 100 completely fill the width of the mold space in a type mold, the guide groove in the mold plate being of greater cross sectional dimensions than the intermediate projection whereby said intermediate projection fits 105 freely therein. 110

3. The combination with a mold cavity and a guide groove in horizontal alinement therewith; of a quad matrix consisting in a single plate of metal having all parts integral therewith and thereby immovable with respect to each other, said plate having one edge constituting a mold confronting edge and provided at its top and bottom corners with lateral projections, said plate having a projection on the mold confronting edge intermediate the aforesaid lateral projections and extending from the body of the matrix a distance substantially equal to 120 said first projections, the width of the inter- 125

130

mediate projection being sufficient to completely fill the width of the mold space in a type mold, one face of said projection being parallel to the mold confronting edge

5 of the matrix and being smooth and unbroken throughout, the guide groove in the mold plate being of greater cross sectional dimensions than the intermediate projection

whereby said intermediate projection fits freely therein.

10

In testimony whereof we hereunto affix our signatures.
